UNITED STATES PATENT OFFICE.

JASON H. GREENSTREET, OF INDIANAPOLIS, INDIANA.

PACKAGE BLANK AND PACKAGE.

1,422,966.

Specification of Letters Patent. Patented July 18, 1922.

Application filed June 4, 1920. Serial No. 386,541.

To all whom it may concern:

Be it known that I, JASON H. GREENSTREET, a citizen of the United States, residing at Indianapolis, in the county of 5 Marion and State of Indiana, have invented a new and useful Package Blank and Package, of which the following is a specification.

The object of my invention is to produce 10 a sheet-and-cleat wirebound box blank, and completed box, in which the sheet and cleat sections are assembled to form the blank with the several sheet and cleat sections materially separated from each other upon the 15 binding wires, so that when the sections are first assembled, a material surplus of binding wire exists at each corner, this surplus being subsequently twisted upon itself so as to draw the sections firmly together at the 20 box corners, thereby making it possible to subject binding wires to adequate tension at each of the box corners.

The accompanying drawings illustrate 25 my invention. Fig. 1 is a perspective view of my improved package in partially assembled condition; Fig. 2 a plan of the blank.

In the drawings, 10, 10 indicate a series 30 of box-side-forming sections consisting of sheets and cleats of a common type. These sections are connected with each other by binding wires 11, which are secured to the sheets and cleats by staples 12.

The sections 10 are associated with the 35 binding wires in such manner that the adjacent edges of the sheets are materially separated from each other, thus providing surplus portions 13 of the binding wires between each pair of sections. The usual end portions 14 of the binding wires are projected beyond the first and final sections 10. By this arrangement, when the sections 10 are folded into position to form four sides of a package, the portions 13 of the wires become U-shaped, as indicated in Fig. 1, 45 and these U-shaped portions are then grasped by a suitable twisting tool and twisted together to form portions 13' (Fig. 1) in such manner as to draw the adjacent portions of adjacent sections 10 tightly together. The portions 13' may then be bent 50 down against the sections 10, as indicated at the lower righthand corner of Fig. 1. The ends 14 are twisted together, in closing the package, as indicated at 14', in the 55 usual manner.

I claim as my invention:

1. A blank for wirebound packages comprising a series of side-forming sections formed for angular association with adjacent sections, said sections being connected together by binding wires and in such spaced relationship to each other that U-shaped surplus of binding wire is formed at the corners of the associated sections.

2. A wirebound package comprising a series of side-forming sections associated with each other in angular relationship edge to edge, and connected together by binding wires having surplus at the package corners, said surplus being twisted upon itself to place adjacent portions of the wire under tension and firmly hold the adjacent edges of adjacent side-forming sections firmly together.

3. The method of making wirebound boxes, which comprises assembling previously-formed independent cleats in longitudinal series with connecting sheet material and longitudinally extending wires, the cleats and connecting sheet material forming a series of package-forming sides, and the wires having such lengths as to provide excessive material between adjacent edges of adjacent side-forming sheets-and-cleats; and twisting the excessive wire portions 85 after the side-forming members have been brought to package-forming relationship.

4. The method of making wirebound boxes, which comprises assembling previously-formed independent cleats in longitudinal series with connecting sheet material and longitudinally extending wires, the cleats and connecting sheet material forming a series of package-forming sides, and the wires having such lengths as to provide 90 excessive material between adjacent edges of adjacent side-forming sheets-and-cleats.

5. A wirebound box blank comprising a plurality of sections flexibly connected together by wires and separated from each other a distance sufficient to provide a surplus of wire which may be doubled and twisted to draw the adjacent sections to box forming positions.

6. A wirebound box blank comprising a plurality of sections flexibly connected together by wires and spaced such a distance apart that the adjacent edges of the sections will be primarily in non-maintainable relation to each other and subsequently asso- 110

ciated in box form by taking up the surplus intermediate portions of wire.

7. A flexible box-blank which is composed of a plurality of sections flexibly connected together by wires and the length of which blank is substantially greater than the dimensions of the finished box require and subsequently associated in box form by taking up the surplus intermediate portions of wire.

8. The process of making a wirebound box, comprising the application of the binding wires of a length to form a surplus at one or more of the corners of the box, and doubling and twisting of the surplus upon itself to tighten the wire around the box.

9. The process of making a wirebound box, comprising the tightening of the wires between the ends thereof, as well as the twisting of the ends of the wires together,

so that each wire is tightened around the box and mechanically tightened on each corner.

10. The process of making a wirebound box, comprising the wiring of the sections of the blank together, with the sections separated from each other a distance greater than is necessary for the dimensions of the finished box, applying the sections to the heads or end walls of the box, thereby forming surplus bends in the wire between the sections, at one or more of the corners of the box, and twisting these surplus bends to tighten the wires.

In witness whereof, I have hereunto set my hand at Indianapolis, Indiana, this first day of June, A. D. one thousand nine hundred and twenty.

JASON H. GREENSTREET.
